UNITED STATES PATENT OFFICE.

JOHN M. MISSOURI, OF MONTROSE, MINNESOTA.

AIR FORCE-PUMP.

1,351,397.

Specification of Letters Patent. Patented Aug. 31, 1920.

Application filed September 12, 1918. Serial No. 253,770.

To all whom it may concern:

Be it known that I, JOHN M. MISSOURI, a citizen of the United States, residing at Montrose, in the county of Wright, State of Minnesota, have invented a new and useful Air Force-Pump; and I do hereby declare the following to be a full, clear, and exact description of the invention, such as will enable other skilled in the art to which it appertains to make and use the same.

This invention relates to an improved air force pump for wells and the like, and one of the objects of the invention is to provide an improved device of this kind, in which there is involved simple, efficient and practical features of construction.

A further object of the invention is the provision of a reciprocating piston, and means for operating the same.

Another object of the invention is the provision of coupled means between the operating mechanism and the piston.

In practical fields the details of construction may necessitate alterations falling within the scope of what is claimed.

The invention comprises further features and combination of parts as hereinafter set forth shown in the drawings and claimed.

In the drawings:

Figure 1 is a vertical sectional view.

Fig. 2 is a horizontal sectional view on line 2—2 of Fig. 1.

Referring more especially to the drawings, 4 designates a suitable casing, which comprises the upper and lower sections 5 and 6, the cylindrical walls 7 and 8 of which are united by threaded connections 9. The lower section 5 is provided with openings 2 for the reception of lag screws (not shown) to fasten or secure the lower section to the well platform (not shown). In order to additionally secure the two sections together bolts 11 pass through the extension flanges of the sections, the lower ends of said bolts are threaded into the lower section, there being suitable packing 12 between the cylindrical wall of the lower section and the top section. Rising upwardly from the bottom section 5 of said casing is a cylindrical wall 13, thereby providing a chamber 14. A cylindrical extension 5^a exteriorly threaded depends from the under surface of the section 5. Threaded to the extension 5^a is a well pipe 5^b, the lower end of which is threaded at 5^c into the top of the well casing 5^d. The well

casing and the well pipe may be any other suitable construction other than shown. Mounted in the chamber 14 is a cap coupling 15, which is provided with an opening 16. This cap coupling has a reduced extension 17 passing upwardly through an opening 17^a of the top section 6, there being a shoulder 17^b, on which the packing 12 adjacent the top section engages. By tightening up on the bolts 11, it is obvious that the cap coupling will be secured firmly in place between the two sections. A pipe 18 extends downwardly into the well casing and through the well pipe 5^b, and has its upper end threaded at 18^a into the reduced extension 17. A second pipe 18^b is threaded at 18^c into the upper end of the extension 17. The upper part of the pipe 18^b has an elbow end 19, to which a bib faucet 20 is threaded. It is obvious that by providing this type of faucet, a suitable hose or the like may be attached by threads to the outlet end 21 of the faucet. Also by the provision of this kind of faucet, the water may be retained in the pipes 18 and 18^b, against the pressure of air below, that is against the pressure of air in the well casing 5^d, by closing the valve of the faucet. The two pipes 18 and 18^b are axially alined, in order to permit a direct passage of the water to the faucet. The cylindrical wall 13 has a lateral part 31, which is integrally connected to the cylindrical wall 32, the interior of which has threads 33. This lateral part 31 is provided with passages formed therethrough, and each passage comprises a restricted portion 34 and enlarged portions 35, and where these passages adjoin a valve seat 36 is provided. Ball valves 37 are mounted in the enlarged portions 35 of said passages, to coöperate with the seats 36, there being transverse pins 38, between which and the valve seats said ball valves are allowed limited movements. A tubular casing 39 (which is provided with a chamber 40) has its lower end threaded into the cylindrical wall 32 by means of the threads 33. The wall of this tubular casing 39 is hollowed out to provide an annular chamber 39^a. This chamber 39^a at its lower end has an annular division wall 39^b, thereby dividing the annular chamber 39^a into upper and lower parts. The upper part of the annular chamber 39^a at its lower portion communicates with the restricted portion 34 of the upper passage

of the lateral part 31, while the lower part 39^a of the annular chamber 39^a communicates with the restricted portion 34 of the lower passage of the lateral part 31. The 5 inner wall of the casing 39 has a port or opening 40^a communicating the chamber 40 with the annular chamber 39^a. The inner wall of the casing 39 at the lower end has an opening or port 40^b, thereby communicating the lower part 39^c of the annular chamber 39^a with the lower end of the chamber 40 that is below the piston 67. A 10 cap 42 is threaded on the upper end of the casing 39, and is provided with an air vent 15 43, with which a check valve 43^a co-operates, for controlling the air into the casing 39. A tubular pump rod 44 reciprocates through the packing gland 45 which is carried by the cap 42. A pump rod section 46 20 has its lower end 47 (which is cylindrical) coupled to the tubular pump rods by means of the turn buckle sleeves 48. The adjacent extremities of the lower end 47 are held spaced from each other, as shown. The 25 turn buckle sleeve 48 is provided with diametrically oppositely disposed openings 49, to permit air to enter the tubular pump rod 44, by way of the space between the adjacent ends of the pump rod and the end portion 47. A second cylindrical tubular casing 50 is in surrounding relation with but spaced apart from the casing 39. This 30 casing 50 is threaded at 51 into the extension 52. The upper end of the casing 50 has a cap 53 provided with a guide opening 55. The guide opening 55 is rectangular, in order to accommodate the corresponding shape of the pump rod section 46. A 35 bracket arm 56 is formed integral with the cap 53, and the lateral part 57 thereof has a guide opening 58, in which the upper end of the pump rod section 46 is guided. The 40 bracket arm 56 has a guide slot 59, and pivoted at 60 to the lug 61 at the base of the 45 arm 56 is a link 62. The upper end of the link 62 is forked and between the forks a lever 63 is pivoted at 64. One end of the lever 63 has its forks 65 pivoted at 66 to the pump rod section 46. By means of an oscillatory movement of the lever 63, a reciprocating movement is imparted to the tubular pump rod 44, the lower end of which is provided with a piston 67. Piston 67 is provided with a check valve which is disposed 50 in a passage which communicates with the tubular pump rod. The guide opening 55 for the pump rod section 46 is of sufficient size to permit air to enter the casing 50. On the upward stroke of the piston 67 its 55 check valve closes the vent 43, and the air (having been drawn through the vent 43 on the previous downward stroke of the piston) will be forced through the port or opening 40^a into the annular chamber 39^a,

and then through the restricted portion 34 65 of the upper passage of the part 31 through the cap coupling, and down through the well pipe 5^b, forcing the water upward through the pipes 18 and 18^b, and out through the faucet, the valve of which having been previously opened. On the downward stroke of the piston 67, the check valve in piston 67 will close, and the air 70 below the piston 67 will be forced from the lower part of the chamber 40 through the 75 restricted portion 34 of the lower passage of the lateral part 31 and into the cap coupling, and thence down through the well pipe 5^b, forcing the water in the well chamber 80 upwardly through the pipes 18 and 18^b and out through the faucet. The check valve 43^a opens on the downward stroke of the plunger 67 and closes on the upper stroke. An outlet passage 81 extends from the chamber 14, and a drain cock 82 is 85 threaded into said passage for draining the refuse from the chamber 14.

The invention having been set forth what is claimed as new and useful is:—

A well pump comprising a casing, said casing comprising a base adapted to be secured to a support, flanges rising upwardly from the base, a flanged cover for said casing secured to the base flanges, a downwardly extending annular flange carried by the base, a casing secured to said downwardly extending flange and having its lower end connected to a well casing, a vertically disposed pipe disposed in said downwardly extending casing and having its lower end disposed in the well casing, a sleeve telescopically engaging the pipe and registering with the opening formed by the downwardly extending threaded flange, said sleeve being of greater diameter than the pipe, an aperture in the sleeve and in communication with the chamber of the casing, the upper end of the sleeve surrounding the pipe being provided with a shoulder adapted to be engaged by the casing cover, the sleeve above the shoulder being interiorly threaded for the reception of the upper threaded end of the pipe and also for the reception of an upwardly extending discharge pipe, and means for forcing air into the casing chamber, through the sleeve aperture and downwardly extending casing to the well casing for lifting the water from the well casing upwardly through the pipe and discharge pipe.

In testimony whereof I have signed my name to this specification in the presence of two subscribing witnesses.

JOHN M. MISSOURI.
